UNITED STATES PATENT OFFICE.

JAMES N. WEIKLY, OF JERSEY CITY, NEW JERSEY.

SAFETY DEVICE.

1,265,845.

Specification of Letters Patent.

Patented May 14, 1918.

Application filed August 14, 1913, Serial No. 784,685. Renewed October 3, 1917. Serial No. 194,594.

To all whom it may concern:

Be it known that I, JAMES N. WEIKLY, a citizen of the United States of America, residing at Jersey City, in the county of 5 Hudson and State of New Jersey, have invented certain new and useful Improvements in Safety Devices, of which the following is a specification.

My invention relates to systems using 10 fluid pressure, particularly railway brakes, and their equipment and the equipment of motors of various characters which employ fluid pressure to operate them or their safety devices or to maintain the pressure 15 system equipment and it consists partly in improved ways of using the devices of the system or systems, and particularly in so arranging and combining the devices, old and new as to automatically accomplish re- 20 sults not heretofore attained.

The invention involves, in part, the use 25 of valves and other appliances so devised and placed that malicious or accidental tampering with or misplacing or deranging of the system, impairing its efficiency and endangering the safety of lives and property, cannot take place without furnishing notice thereof to those in the vicinity or those 30 whose attention should be attracted to the situation. Not only so, but they provide that in some systems, the derangement shall automatically apply brakes and keep them applied till the defect or misplacement is remedied and then resume normal condition 35 40 ready to announce any subsequent derangement, having also kept guard in the interim and against any increase in the derangement.

It is in effect a safety device and guards 45 against the fallibility of man.

The human factor cannot be eliminated from railroad work nor from many other varieties of work, and it is upon the human element that we must, to some extent, de- 50 pend, but my effort has been to provide a system so devised, arranged and combined, that, as a whole, it efficiently aids the human element and leaves no avoidable avenue for mistake.

At times the voluminous duties of a locomotive engineer, during the rush and tumult of his motor, running at high speed, particularly at night, when the light is poor or absent and he must be watching ahead for 55 the signals and operating the levers and

other multifarious devices requiring his attention, confined in a narrow space, and with the air pump out of sight and reach, are such that it is beyond human powers to guard absolutely against the stopping of the 60 pump and the loss of air, and because of these conditions, accidents sometimes happen that with prior systems are practically unavoidable, but which could be avoided if the situations were known, and it is to the 65 task of making known and (in some cases) to the preventing of movement till the defect is remedied, that I have given my attention.

Sometimes a brake valve is inadvertently 70 left on lap, which is worse than having an angle cock turned on the tender, so I have provided for announcing this also.

Each of my devices has its own important 75 and automatic duty to perform, sometimes separately and sometimes in combination, but when properly arranged as specified, they unitedly constitute a complete guardian system which will announce and substantially compel recognition of any dangerous 80 condition.

Figure 1 is a view of two cars and a locomotive, the couplings of which are provided with peculiar angle cocks embodying my invention. The cab of the locomotive is 85 provided with a pump indicator and a guardian equipped with an annunciator, as well as other devices which are a part of the system.

Fig. 2 is a face view of one of the angle 90 cocks, showing the parts in the positions they occupy in service.

Fig. 3 is an end view of the angle cock of Fig. 2.

Fig. 4 is a view of an angle cock of the 95 same general character, but having some additional features of value.

Fig. 5 is an end view of the device of Fig. 4.

Fig. 6 is a side view of the plug of Fig. 2. 100

Fig. 7 is a cross sectional view of the plug and casing of the angle cock of Fig. 2.

Fig. 8 is a cross sectional view of the same device when the plug is turned about 85°.

Fig. 9 is a similar view of said parts when 105 the plug is turned a full quarter.

Fig. 10 is a cross sectional view of an angle cock in which the channels are cut in the casing.

Fig. 11 is a similar view of an angle cock 110

from which the passage 30 is omitted, but in which the passage 27 is cut through to passage 29.

Fig. 12 is a cross sectional view of the angle cock of Figs. 4 and 5, which may be set so as to prevent the passage of any air through it.

Fig. 13 is a sectional view, on the same line as Fig. 12, of a form of angle cock provided with an outer and an inner bleed, one of which closes in advance of the other.

Fig. 14 is a sectional view of such a cock, in which the two bleed ports are at different levels.

Fig. 15 is a sectional view of the two level bleed plug and casing, taken at the level of the upper bleed.

Fig. 16 is a side view of the plug of Figs. 14 and 15, showing the passages for the lower bleed.

Fig. 17 is a side view of the same plug, showing the passage for the upper bleed.

The devices shown are all a part and parcel of an air brake system for railroad trains, though I do not limit my claims to such an installation. They consist in an indicator arranged to show every movement of the pump which creates the needed air pressure, an annunciator and also an angle cock so constructed and designed that it will bleed the train line when it is turned, and so connected to an annunciator that such bleeding will be announced to the operator or engineer, provided the devices are properly designed and assembled.

With such a system, thus arranged, the engineer is provided with checks against the heretofore uncovered spaces in the chain of safety.

As one step in that direction I provide a new angle cock of my devising. It is located as usual at the end of the car and in the train pipe of the air brake system.

It is so constructed as to bleed as soon as the plug is turned slightly out of position, and to bleed so freely, when further turned, that the brakes will be automatically applied.

The bleeding is utilized to operate a signal in the cab and thus notify the engineer that the plug of an angle cock is out of proper position and may also be utilized to give such a sign or warning to trainmen as to save time by immediately indicating the location of the defect.

This part of the system may be constructed in several different ways, I prefer the form shown in Figs. 1, 4, 5, 12, or 2, 3, 6, 7, 8, 9. There is first, the casing 14 preferably large enough to accommodate a plug provided with passages of a capacity as great or greater than the pipe of the train line, shown at 12.

This casing holds a large plug 15, preferably tapered, and held in place by a flanged

cover 16, threaded into the casing. The opposite end of the plug is reduced, squared and provided with a collar 17, which is pivoted to the lever or handle 18, and provided with a lever stop 19, and a downward projection 20, which will take against one or the other of the stops 21, 22, 23, on the casing. The lever 18 is apertured to embrace the collar 17, and provided with a downwardly projecting stop 10, adapted to take behind stop 22 and thus lock the device in full service position, and another adapted to take behind stop 21 and lock the device when turned a full quarter.

When the lever 18 is raised, it lifts stop 10 out of the locked position and the lever may be swung to the right, the stops 20 and 21 preventing movement in the other direction.

Stop 20, will also prevent the movement of the plug for more than the prescribed distance, since at that limit it will strike against stop 22 and arrest the turning of the plug, and then the lever may be depressed so that stop 11 will take behind stop 21.

Stop 23 is provided to facilitate rapid operation. When the lever 18 is swung to cut off the air from the train side of the angle cock, that may be fully accomplished in the device of Figs. 4, 5, 12, before the hose side is fully closed. The contact of stops 20 and 23 announces the fact. Then the operator can raise the lever so as to clear 23, swing it the balance of the quarter and then force it down to the locked position.

This plug 15, is, as already stated, pierced with a passage way 24, leading from the port 25, of the casing, (connected with one section of the train pipe,) to the port 26 of the casing, which is connected to the next section of the train pipe or hose.

The plug also has channels 27, 28, 29, cut in its face, (in some forms) and a passage 30 cut from passage 24, to channel 27 and the casing is provided with a passage way or port 31, leading entirely through the casing. The channel 29 is preferably quite narrow for a short distance and then spreads so as to give vent to a considerably greater quantity of air than is being supplied from the reservoir.

I prefer to cut it of such a length that the smaller end will begin to register with passage 31, as soon as the plug has turned as much as 6° . Then by properly forming and proportioning the stops 10, 21, 23, it will result that as soon as the valve handle has turned so far that stop 10 rides on the face of stop 22 and the handle can no longer return by gravity to its locked position, the bleeding will begin.

The capacity of the channel should be such that by the time it has turned say 20° , the opening will be sufficient to permit the

escape of so much air as to lower the pressure in the train pipes enough to result in applying the brakes and this it must be remembered involves not only the release of 5 the air then in the train pipe, but also of that which would flow therein from the reservoir.

Channel 28 is provided to permit the bleeding from the carside section of the train 10 pipe, after the port of passage 24 has ceased to register with port 25 and I preferably make it long enough to continue such bleeding till the plug has been turned about 84°.

Passage 30 and channel 27 are provided 15 to permit the bleeding from the hose section to continue until the plug is turned more than 84 degrees (if form 12 is used), or until reversed and carried back to very nearly the first position, if form 7 is used.

20 In form 12, passage 30^a is set sufficiently on one side to leave uncut a wide enough part of the side face of the plug to entirely close port 31, but in form 2 it is otherwise set and channel 27, is long enough to continue the registry with port 31 during the remainder of the quarter turn of the plug, any interruption, by reason of the blank from the end of 24 to the end of 29, is easily prevented by widening 26 as shown.

25 The special purpose of the arrangement of Figs. 4, 5, 12, is this. Sometimes the train pipe of a car gets out of order and it is desirable to place that car at the rear of the train and to shut off the air from that car's 30 brake, but to leave it at full pressure in the train pipe and hose, up to the angle cock on that car. With this form of device the lever can be quickly swung a full quarter, thereby cutting off the car and at the same

35 time leaving the train pipe, including the hose, up to that cock, in running condition, because a full quarter cuts off all transit through that plug. Then if that car breaks loose from the train, the parting of the hose 40 would apply the brakes, on the train. This would not occur if the preceding angle cock were closed, as it must be if transit through the succeeding one can not be entirely cut off.

45 Again it sometimes happens that a car is to be quickly shunted to a siding and it is desirable to leave the pressure on on that car to permit the train man to control it after it is cut off, but at the same time he

50 desires to reduce the pressure in the hose, so that the uncoupling may be readily effected. Under those conditions, he quickly swings the lever of the angle cock, on the car to be uncoupled, a full quarter so as to 55 shut off any escape of air from its train pipe. Then he swings the lever of the angle cock on the preceding car around for about 80° (in this form) though the degree may be changed if desired. That will shut off

60 65 air from its train pipe, but leave the bleed

open from the hose side, the engagement of stop 20 with stop 23, announcing to the train man that that point has been reached. An instant's hesitation is then sufficient to exhaust the hose portion to atmospheric 70 pressure, and then the train man can lift his lever over stop 23, complete the movement of lever 18 and force it down into the desired locked position, thus accomplishing very easily all that he desires to do. If it 75 be desirable that the bleeding from the hose side of the cock be continued after the car side is cut off, the form of Figs. 2, 3, 7, 8, 9, 10, 11, 13, 14, may be employed, instead of the form just described. That form however does not permit the holding of the hose 80 full when an adjacent car is cut out.

A further reason for desiring to continue the bleeding from the hose, beyond the car, after the car side is cut off, is to lower the 85 pressure in those sections of hose between the angle cock on one car and that on the next car, to the normal atmospheric pressure, to prevent injury to the train men, relieve the strain on the hose and its coupling, avoid 90 injury to the gaskets and to accomplish various other important ends.

At the same time, undue loss of air, such as would set the brakes, should be avoided when the cars are being legitimately coupled or uncoupled and for that reason I 95 construct the plug so that when turned a full quarter it will not bleed from the side toward the car to which the angle cock is affixed, that is, port 25.

100 I have shown 6 structures, having channels in the plug, for accomplishing the desired result. Fig. 10 shows one in which the necessary channels are located in the shell instead of the plug, and Fig. 11 105 shows a form which dispenses with the passage 30, by constructing passage 29 (29 and 27) so long that communication from it to port 26, once initiated, is not cut off till the plug is reversed. Of course one could be 110 easily made in which one or more channels were located in the plug and the remainder in the casing. Sometimes it is desirable that the bleeds should be such as to more fully inform the train man of their character. To do this I arrange a double bleed, 115 one outward and one inward.

In Fig. 13 they are shown on the same level. A passage 66, is provided on that side of the casing toward the nearest side of 120 the car, bleed 31 being on the other side. Then I cut another passage 65, from passage 24 to the face of the plug, on the level of bleed 66, but about 6° distant. As soon as the plug is turned 6°, the bleeds 66 and 31 125 give vent to the air. The length of the ports of 66 and 65 may be proportioned to give vent as long as desired and by regulating the length of passage 28, the general bleed will be announced by air passing from 66, 130

as long as passages 28 and 25 are in registry. When that ceases the train man knows that air from the car side is cut off and the continuance of the bleed from 31 announces 5 that the bleed from the hose side continues. It can be regulated by shortening 27.

In the other double bleed device there is a bleed passage 68, leading toward the outside (as does passage 66), but on a different 10 level from bleed 31. Then I provide a passage 67 leading from the main passage 24, of the plug, up to the level of bleed port 68 and terminating in a port 69, of sufficient size to open when the plug has turned but 15 slightly and to remain open as long as port 25 is open, (using or omitting passage 28 as desired). Now as soon as a bleed is started, the fluid will spurt out at both bleed ports, but when the train man turns the lever till 20 it ceases to spurt toward him, he will know that the cock is closed on the car side. 31 is still open. If he holds the plug in that position till no fluid issues from the other bleed port 31, he will know that pressure in 25 the hose has decreased to that of the atmosphere and he can then close the cock absolutely or not as his orders may direct and the particular form of device employed may permit, that is, if 27 be shortened enough he 30 may close it absolutely, if as long as shown, and the other parts as shown, he could not.

What I claim as my invention and desire to secure by Letters Patent is:—

1. A valve analogous to an angle cock of 35 a train line and composed of a stationary part and a movable part, a through way in each, adapted to register one with the other, said parts being provided with a plurality of vents, one of which opens at a different 40 radial point from the other, and passages adapted to register with the ports of said vents at different intervals in the movement of the movable part.

2. A valve analogous to an angle cock of a 45 train line and composed of a stationary part and a movable part, through ways in each adapted to register one with the other, said parts being provided with a plurality of vents, one of which opens at a different radial point from the other, and with passages 50 adapted to register with the ports of said vents at different intervals and in the movement of the movable part and with passages leading from the throughway to said first 55 named passages.

3. A valve analogous to an angle cock of a train line and composed of a stationary part and a movable part, through ways in each, adapted to register one with the other, said 60 parts being provided with a plurality of vents at different levels, one of which opens at a different radial point from the other, and with passages adapted to register with the ports of said vents at different intervals 65 in the movement of the movable part.

4. An angle cock provided with a casing adapted to be connected to the car section and to the hose section of a train line and provided with a vent, a plug located in said casing and adapted to register with the ports of the through way of the casing for a portion of the movement of said plug and a passage whose port is adapted to register with the port of said vent during a part of the period of registry of the through way ports, the face of a part adjacent to the line of contact between the plug and casing being provided with a channel which extends some distance along said face, greater than the port opening of the vent passage. 70

5. An angle cock composed of a plug and a casing provided with a vent opening directly to the open air and ports and passages, substantially as described, whereby the vent opening is in registered connection with the through way of the plug for more than half of the throw of said plug, but closed again before the plug has moved a full throw. 75

6. A valve analogous to an angle cock, 80 composed of a plug and a casing provided with a vent opening and ports and passages, substantially as described, whereby the passage of air through the plug from the train pipe connection at one end to the train pipe 85 connection at the other end is maintained from full service position till near the end of the full throw of the plug lever, but the passage which includes the casing inlet, the casing outlet and the vent, is closed at some 90 point, before the throw of the plug is completed, all substantially as set forth. 100

7. A valve analogous to an angle cock, composed of a plug and a casing provided with an unobstructed vent opening and ports 105 and passages in plug and casing, substantially as described, whereby the vent opening directly to the open air is in registered connection with the through way of the plug for more than half of the throw of said plug, but the passage which includes the casing inlet, the casing outlet and the vent, is closed at some point, before the throw of the plug is completed, all substantially as set forth. 110

8. A valve analogous to an angle cock, composed of a plug and a casing with a vent opening and ports and passages in plug and casing, substantially as described, whereby both through ways in the casing from the 115 train pipe connection at one end to the train pipe connection at the other end will remain in communication with the through way in the plug for more than half of the throw of the plug, but the passage which includes the casing inlet, the casing outlet and the vent, is closed at some point, before the throw of the plug is completed, all substantially as set forth. 120

9. A valve analogous to an angle cock, 130

composed of a plug and a casing provided with a vent, a lever and stops, one of which is set as described whereby the moving part will make contact with said stop when one side of the casing is open and the other is closed, but before the plug has reached the limit of its full throw, all substantially as set forth.

In testimony whereof, I have signed my name to this specification in the presence of two subscribing witnesses, this 8th day of August, 1913.

JAMES N. WEIKLY.
